AIR CONDITIONING SYSTEM

William J. Aulsebrook, Evansville, Ind., assignor
to Servel, Inc., New York, N. Y., a corporation
of Delaware

Application April 25, 1935, Serial No. 18,113

14 Claims. (Cl. 62—6)

My invention relates to refrigeration and more particularly to air conditioning with refrigeration apparatus.

It is an object of my invention to provide an improved arrangement for regulating conditioning of air by means of a refrigeration apparatus, as will appear upon consideration of the following description taken in connection with the accompanying drawing forming a part of this specification and of which:

The figure shows more or less schematically an air conditioning system embodying my invention.

Referring to the drawing, an air duct, generally indicated by the reference character 10, is constructed to form a main passage 11 and a by-pass passage 12. A suitable fan or blower 13 causes air to be drawn into the inlet end 14 of the air duct and discharged at the outlet end 15 of the air duct. Relative flow of air through the main passage 11 and the by-pass passage 12 is regulated by a damper 16 of a known type comprising a plurality of shutters in the by-pass passage 12 and which are operated together by a suitable operating rod 17.

In the main passage 11 of the air duct 10 is arranged a cooling element 18 of a compression type refrigeration apparatus which also includes a motor driven compressor 19 and a condenser 20. The cooling element 18 is shown in the form of a coil having loops extending generally perpendicular to the flow of air through the passage 11 and provided with heat transfer plates or fins extending generally perpendicular to the loops and substantially parallel to the flow of air in the passage 11. The refrigeration apparatus contains a suitable cooling fluid which is compressed in the compressor 19, liquefied in the condenser 20, and evaporated in the cooling element 18. Compressed refrigerant vapor flows from the compressor 19 through conduit 21 to the condenser 20. Liquefied refrigerant flows from the condenser 20 into a receiver 22. From the receiver 22, liquid refrigerant flows through conduits 23 and 24 into one end of the coil of the cooling element 18 under the control of a suitable pressure reducing or expansion valve 25. The expansion valve 25 is operated by a thermostat 26 responsive to temperature at the outlet end of the coil of the cooling element 18. Refrigerant vapor flows from the outlet end of the coil of the cooling element 18 through conduit 27 back to the compressor 19. Operation of the compressor 19 may be controlled in any desired manner by a suction

pressure or cooling element temperature control switch, not shown.

When the damper 16 is fully closed, all of the air drawn through the duct 10 flows through the main air passage 11 in thermal exchange relation with the cooling element 18. When the damper 16 is fully open, air flows through both the main passage 11 and the by-pass passage 12 in proportions relative to the respective resistances to air flow to these passages. This relative air flow through the passages 11 and 12 may be varied by moving the damper 16 between its fully open and fully closed positions. For the purpose of operating the damper 16, I provide a device comprising a lever 28 pivoted at 29, an expandable bellows 30 arranged in operative relation with one end of the lever 28, and a load spring 31 which may be adjusted by a screw 32. The damper operating rod 17 is connected to the longer end of the lever 28 so that the movement of the expandable bellows 30 may be multiplied in operating the damper 16. The expandable bellows 30 is connected by means of a conduit 33 and a conduit 34 to the conduit 23 which is in the high pressure side of the refrigeration apparatus. The bellows 30 is also connected by means of conduit 33 and a conduit 35 to the conduit 24 which is in the low pressure side of the refrigeration apparatus. In conduit 34 is a solenoid operated valve 36 and a similar valve 37 is provided in conduit 35.

In the discharge end 15 of the air duct is arranged a three point humidostat 38. The movable contact 39 of the humidostat is connected to one side 40 of an electric circuit. One fixed contact 41 of the humidostat is connected by a conductor 42 to one side of the solenoid which operates the valve 37. The other fixed contact 43 is connected by a conductor 44 to one side of the solenoid which operates the other valve 36. The other side 45 of the electric circuit is connected in common to the other sides of the solenoids which operate valves 36 and 37 by conductor 46 and conductors 47 and 48 respectively.

The humidostat is represented more or less schematically and shows a simple snap-action toggle 50 for imparting quick motion to the contact 39. Under normal conditions, the humidostat contact 39 stands closed against contact 41 so that valve 37 is energized and open and valve 36 is de-energized and closed. The bellows 30 is connected by conduits 33 and 35 to the conduit 24 in the low pressure side of the refrigeration apparatus. The damper 16 will assume a position determined by the adjustment of the spring 31 which opposes the action of the bellows 30 on

the lever 28. If the pressure in the cooling element 18 rises, tending to deliver air of higher relative humidity at the outlet 15, this rise in pressure will be exerted through bellows 30 to open the damper 16 and thus by-pass a portion of the air, or more of the air, through the passage 12. This relief of load on the cooling element 18 will permit the refrigeration apparatus to lower the temperature of the coil until a balance is again established and air of proper moisture content is delivered from the coil.

It will be understood that this device will function as an unloader at the time of starting the refrigeration apparatus. In the event that the cooling element 18 has been allowed to become warm during a shut-down, the high pressure in this side of the apparatus at starting will cause the damper 16 to take a wide open position and thus divert a large portion of the air around the cooling element 18 until the compressor is able to reduce the temperature of cooling element 18 to its normal operating temperature.

Upon extreme conditions of load, if the normal by-pass regulation of air flow in response to low side pressure, as described, fails to maintain the relative humidity of delivered air below a predetermined limit, the humidostat 38 will cause the contact 39 to break from the normal contact 41 and close on the contact 43. Thereupon, the valve 36 becomes energized and opens and valve 37 becomes de-energized and closes. When valve 36 opens, high pressure liquid in conduit 23 of the refrigeration apparatus is admitted through conduits 34 and 33 to the bellows 30. This causes an abnormal expansion of the bellows 30 which in turn operates the lever 28 to open the damper 16 to an extreme position which may be predetermined by a stop 49 for the lever 28. The wide open damper 16 allows for maximum by-pass of air through the passage 12 until the refrigeration apparatus can reduce the temperature of the cooling element 18 so that the humidity requirement of the humidostat 38 is satisfied. Thereupon, the humidostat will return to its normal position and operation continue as previously described.

It will be understood that instead of a humidostat 38 I may employ a thermostat and reverse the action of the damper mechanism with respect to the operation of the bellows 30. This results in opening of the by-pass damper 16 when the air temperature is below normal and closing of the damper when normal temperatures are restored. It will also be understood that the control humidostat 38 or thermostat may be located in a space such as a room to be conditioned instead of in the supply duct as indicated. I may also employ a fixed orifice or capillary tube in place of the normally open valve 37 and thereby eliminate the need of a third point on the humidostat or thermostat.

It will be understood that various changes may be made within the scope of my invention which is therefore not limited to that which is shown in the drawing and described in the specification but only as indicated in the following claims.

What is claimed is:

1. In combination, means for conditioning air including a refrigeration apparatus having high and low pressure sides, pressure responsive means for regulating relative flow of air to be conditioned with respect to said conditioning means, and means for selectively connecting said pressure responsive means to the high and low pressure sides 75 of said apparatus.

2. In combination, means for conditioning air including a refrigeration apparatus having high and low pressure sides, pressure responsive means for regulating relative flow of air to be conditioned with respect to said conditioning means and connected to the low pressure side of said apparatus, and means for connecting said pressure responsive means to the high pressure side of said apparatus responsive to an abnormal air condition.

3. In combination, means forming a conduit for flow of air, a blower for causing flow of air through said conduit, refrigeration apparatus having high and low pressure sides and including a cooling element in said conduit, means forming a by-pass passage for flow of air around said cooling element, a damper for regulating flow of air through said by-pass passage, pressure responsive means for operating said damper and including an expandable bellows, a conduit connecting said bellows to the low pressure side of said refrigeration apparatus, a conduit connecting said bellows to the high pressure side of said apparatus, a solenoid operated valve in each of said conduits connecting the bellows to said refrigeration apparatus, and a three point psychrometric instrument arranged in the path of flow of air beyond said cooling element and arranged to selectively connect said solenoid operated valves to a source of electricity.

4. In combination, refrigeration apparatus having high and low pressure sides and including a cooling element, means forming a path of flow for air in contact with said cooling element and a by-pass passage for flow of air around said cooling element, a damper for regulating flow of air through said by-pass passage, pressure responsive means for operating said damper and including an expandable bellows, a conduit connecting said bellows to the low pressure side of said refrigeration apparatus, a conduit connecting said bellows to the high pressure side of said apparatus, a solenoid operated valve in said conduit connecting the bellows to the high pressure side of said refrigeration apparatus, and an air condition responsive device in the path of flow of air beyond said cooling element and arranged to connect said solenoid operated valve to a source of electricity.

5. In combination, refrigeration apparatus having high and low pressure sides and including a cooling element, means forming a path of flow for air in contact with said cooling element and a by-pass passage for flow of air around said cooling element, a damper for regulating flow of air through said by-pass passage, pressure responsive means for operating said damper and including an expandable bellows, a conduit connecting said bellows to the low pressure side of said refrigeration apparatus, a conduit connecting said bellows to the high pressure side of said apparatus, a valve in each of said conduits connecting the bellows to said refrigeration apparatus, and an air condition responsive device in the path of flow of air beyond said cooling element and arranged to selectively operate said valves.

6. In combination, means forming a conduit for flow of air, a blower for causing flow of air through said conduit, refrigeration apparatus having high and low pressure sides and including a cooling element in said conduit, means forming a by-pass passage for flow of air around said cooling element, a damper for regulating flow of air through said by-pass passage, pres- 75

sure responsive means for operating said damper, and an air condition responsive device in the path of flow of air beyond said cooling element and arranged to selectively connect said pressure responsive means to the high and low pressure sides of said apparatus.

7. In combination, means forming a conduit for flow of air, a blower for causing flow of air through said conduit, refrigeration apparatus having high and low pressure sides and including a cooling element in said conduit, means forming a by-pass passage for flow of air around said cooling element, a damper for regulating flow of air through said by-pass passage, and pressure responsive means for operating said damper and connected to the low pressure side of said refrigeration apparatus.

8. In combination, means forming a conduit for flow of air, a blower for causing flow of air through said conduit, refrigeration apparatus having high and low pressure sides and including a cooling element in said conduit, means forming a by-pass passage for flow of air around said cooling element, a damper for regulating flow of air through said by-pass passage, pressure responsive means for operating said damper connected to the low pressure side of said refrigeration apparatus, and means to connect said pressure responsive means to the high pressure side of said apparatus responsive to an abnormal air condition.

9. Apparatus for conditioning air including a refrigeration system comprising members forming a circuit for refrigerant fluid, a device for regulating flow of air to be attempered by said system, and a pressure actuated device having movement through distances functionally related to changes in pressure and connected to operate said air regulating device, said pressure device being connected to said circuit so as to be subjected to pressure therein.

10. Apparatus for conditioning air including a refrigeration system comprising members forming a circuit for refrigerant fluid and devices for maintaining one part of said circuit at a higher pressure than the other part of said circuit, a device for regulating flow of air to be attempered by said system, and a pressure actuated device

having movement through distances functionally related to changes in pressure and connected to operate said control device, said pressure device being connected to the low pressure part of said circuit so as to be subjected to the pressure therein.

11. A method of conditioning air which includes circulating refrigerant fluid in a closed circuit in a manner so that the fluid is evaporated to produce a cooling effect in one part 10 of the circuit, subjecting air to the cooling effect, and regulating the air subjected to the cooling effect by amounts functionally related in changes in force within said circuit.

12. A method of conditioning air which includes condensing refrigerant fluid at a certain pressure, evaporating the condensed fluid at a lower pressure to produce a cooling effect, subjecting air to said cooling effect, and regulating the air subjected to said cooling effect by 20 amounts functionally related to changes in said lower pressure.

13. Apparatus for cooling fluid including members forming a circuit for refrigerant fluid, a device for regulating flow of fluid to be cooled 25 by a portion of said circuit, and a pressure actuated device having movement through distances functionally related to changes in pressure and connected to operate said regulating device, said pressure device being connected to 30 said circuit so as to be subjected to pressure therein.

14. Apparatus for cooling fluid including members forming a circuit for refrigerant fluid, devices for causing condensation of refrigerant 35 fluid at a high pressure in one part of said circuit and evaporation of the condensed fluid at a lower pressure in another part of said circuit, a device for regulating flow of fluid to be cooled in thermal exchange relation with the low pressure part of said circuit, and a pressure responsive device having movement through distances functionally related to changes in pressure and connected to operate said regulating device, said pressure responsive device being connected to 40 the low pressure part of said circuit so as to be subjected to the pressure therein.

WILLIAM J. AULSEBROOK.
